(57) **CLAIM**

The ornamental design for a roof support structure with peripheral support strap grooves, as shown and described.

DESCRIPTION

FIG. 1 is a perspective view of an embodiment of a roof support structure with peripheral support strap grooves comprising an upper core member and a plurality of attached lower cover layer members comprising an elastomeric polymer foam;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view of a second embodiment of a roof support structure with peripheral support strap grooves comprising an upper core member and an attached lower cover layer member comprising an elastomeric polymer foam;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a rear view thereof.

The roof support structure with peripheral support strap grooves is shown with a symbolic break in its length. The appearance of any portion of the article between the break lines forms no part of the claimed design.

The roof support structure with peripheral support strap grooves includes integral right end and left end pockets comprising handles or grips and a plurality of upwardly protruding traction members that are shown in broken lines. The broken lines shown in FIGS. 1-2, 4-9, and 11-14

(Continued)

illustrate portions of the roof support structure with peripheral support strap grooves that form no part of the claimed design.
